LELA B. WEIR, OF LOS ANGELES, CALIFORNIA.

ADJUSTABLE HAT LINING.

Application filed October 8, 1927. Serial No. 224,793.

This invention relates to adjustable hat linings and an important object of the invention is to provide for adjustability in the height of the lining so that the hat, in which 5 the lining is placed, can be easily adjusted to the wearer's head.

It is the present practice, in order to obtain proper adjustment of women's hats, as to the height that the hat is positioned on 10 the head, to initially make the hat lining approximately as deep as the crown of the hat and then, if the hat is positioned too low on the purchaser's head, a tuck is taken in the lining, generally in the rear portion thereof, 15 so as to diminish the depth of the said lining and cause the crown of the hat to rest higher upon the head. This method of adjusting the lining requires considerable time and it is frequently the case that the depth of the 20 lining must be altered several times in order that the crown of the hat may be properly held in position on the head.

This invention makes possible very quick adjustment in the depth of the lining, as no 25 sewing is required.

Other objects and advantages will appear in the subjoined detailed description.

The accompanying drawings illustrate the invention.

30 Figure 1 is a vertical section of a hat lining constructed in accordance with the provisions of this invention, the body of the hat being indicated in dotted lines.

Figure 2 is a view similar to Figure 1 excepting that a reef or fold has been taken in the lining to reduce the depth thereof.

Figure 3 is a vertical section on the line indicated by 3—3, Figure 2.

Referring to the drawings the body of the 40 lining is indicated at 4 and is cup-shaped and is constructed of any of the materials commonly employed for that purpose. As is well known in this art, such lining materials are of a limp or flimsy character and, as 45 accordingly, will readily fold. In the drawings, the lining 4 is shown in position within the body of the hat, said body comprising a crown *a* and a brim *b*. The body of the hat is only indicated for the purpose of making clear how the invention operates.

50 A means is provided for taking a reef or making a fold in the lining body 4 depthwise of the lining body and for this purpose, the lining is provided with upper perforations 5 and lower perforations 6. The perforations

5 and perforations 6 are arranged in pairs and the perforations comprised in each pair are preferably comparatively close together while the pairs of perforations are comparatively far apart. There are also provided 60 other perforations 7 arranged in pairs along a plane that extends substantially mid-way between the perforations 5 and perforations 6.

Through the perforations 5, 6, 7 is threaded a draw string 8. In this particular instance the draw string 8 is in two sections, although it will be readily understood that the draw string may be made of one piece, if desired. However, the advantage of having 65 the draw string in two sections is that in making the adjustment the two sections may be drawn at their ends so as the more easily to take up the lining body uniformly from end to end of the portion in which the reef 70 or fold is made. Preferably such portion is in the rear of the lining body as this is the portion it is usual to change the height of.

75 Each draw string section comprises portions 9 that extend diagonally away from 80 one another toward the middle of the back portion of the lining body on the outside of said body, portions 10 on the inside of the lining, other portions 11 on the outside of the lining body and still other portions 12 on 85 the inside of the lining body. The portions 11 of one of the draw string sections cross the portions 11 of the other draw string section. Preferably the perforations 5, 6, 7 have their edges protected by suitable means 90 as, for example, eyelets 13 so as to guard against the fabric being torn or frayed at the perforations. Buttonhole stitching may be used in lieu of the eyelets if desired.

95 The ends of the draw strings are releasably connected by a suitable means such, for example, as bow knots 14.

The invention above described operates as follows: Assuming, for example, that the draw string 8 is adjusted to permit of maximum depth of the lining body 4, as in Figure 1, and that the hat has been tried on the customer to ascertain whether it fits properly and that it is found advisable to decrease the depth of the lining so as to hold the hat 105 higher on the head, the hat will be removed from the head, the bow knots 14 untied and the draw strings 8 will then be pulled, thus causing the perforations 5 to approach the perforations 6, thereby producing a reef or 110

fold 15 in the lining body 4. This results in lowering the top of the lining body or in other words, reducing the depth of said body as clearly shown in Figure 2. The ends of the draw strings will then be retied so that the perforations 5, 6 will be maintained in the positions to which they have been adjusted by pulling of the draw string. The hat will then again be tried on the customer's head and, if not found to fit properly, the draw string will again be adjusted. This adjustment will be repeated as many times as necessary to secure the desired results.

During the adjusting of the draw string, if the lining body should be reduced somewhat in diameter by reason of the perforations 7 at one side being drawn toward the perforations 7 at the other side, the lining body will again be stretched to its original diameter by the head of the customer as it enters the hat.

While I have illustrated and described a particular construction for slidably connecting the draw string 8 with the body 4 so as to extend around said body between the top and edge of said body and so that a portion of the draw string is connected with the body at a higher level than another portion of said draw string in order that tightening of the draw string will reduce the depth of the body, it is to be understood that any other suitable means for slidably connecting the draw string with the

body may be substituted for the elements 5, 6, 7 within the scope of the invention.

35

I claim:

1. An adjustable hat lining comprising a cup-shaped body of limp lining material, and a draw string slidably connected with said body, a portion of said draw string being connected with the body at a higher level than another portion of said draw string so that tightening of the draw string will reduce the depth of the body.

2. An adjustable hat lining comprising a cup-shaped body of limp lining material, and a draw string slidably connected with said body and extending around said body between the top and edge of said body, a portion of said draw string being connected with the body at a higher level than another portion of said draw string so that tightening of the draw string will reduce the depth of the body.

3. An adjustable hat lining comprising a cup-shaped body of lining material, and a drawstring slidably connected with said body at a plurality of places at two different levels, the lining material being of such a character as to form a fold between the upper and lower connections when the drawstring is tightened.

Signed at Los Angeles, California, this 29 day of September, 1927.

LELA B. WEIR.
